[57] CLAIM

The ornamental design for a bottle, as shown and de-
scribed.

DESCRIPTION

FIG. 1 is a front elevational view of a bottle, showing
my new design;

FIG. 2 is a top plan view thereof; and,

FIG. 3 is a bottom plan view thereof.

The rear elevational view is identical to FIG. 1 except
that the received element appearing at the bottom of
FIG. 1 is present only in the front as shown in FIG. 1.
